WASHING MACHINE

Filed May 7, 1929

Inventor
Wilhelm Rath
By his attorney
Marie Raabe

UNITED STATES PATENT OFFICE

WILHELM RATH, OF NEW YORK, N. Y.

WASHING MACHINE

Application filed May 7, 1929. Serial No. 361,116.

This invention relates to improvements in washing machines particularly to a hand-operated washing machine and apparatus for small articles, such as handkerchiefs etc.

5 It is the principal object of my invention to provide a machine of simple and comparatively inexpensive construction, yet durable and efficient in operation.

Another object of my invention is the provision of a washing machine of this character equipped with a plate valve for allowing the escape of the air, yet preventing water from entering the operating chamber.

A further object of my invention is the 15 provision of a machine of the above described type finding a firm support in a wash-tub or the like receptacle.

These and other objects and advantages of my invention will become more fully known 20 as the description thereof proceeds, and will then be specifically defined in the appended claims.

In the accompanying drawing forming a material part of this disclosure:

25 Fig. 1 is a sectional side elevation of a washing machine constructed according to my invention.

Fig. 2 is a top plan view thereof in section on line 2—2 of Figure 1.

30 Fig. 3 is a bottom plan view in section on line 3—3 of Figure 1.

As illustrated, the machine constructed according to my invention comprises a base 10, adapted to be placed into a tub, and firmly 35 held against the bottom thereof by means of the rubber mounted pads 11 which are held between the arms of the brackets 13 and are secured thereto by means of rivets 14 or the like.

40 The brackets 13 are formed with or integrally made with a housing 15 closed on top by means of the foot 16 of a cylindrical casing 17 having an elongated opening 18 in its wall, and closed on top by means of a 45 cover 19.

A plunger or piston rod 20 within cylinder 17 and extending with its lower end into casing 15 has secured to said lower end a piston 21 enclosing a rubber packing 22 marginally 50 extending therefrom to produce a tight clo-

sure between piston and inner walls of casing 15.

The piston has formed therein a port or ports 23 for the escape of the air.

In order to prevent the escape of water 55 from the lower part 24 of the compartment 15, into which the articles to be washed are placed, a plate valve 25 is provided movable within a casing or housing 26 formed with the lower face of the piston allowing the 60 escape of air through ports 23 during the downward movement of the piston 21, which is held on its rod by means of nuts 27, 28, or the like.

A handle 29 extends with its shaft through 65 slot 18 into cylinder 17 and is secured to rod 20 by means of a bracket or socket 30, or otherwise.

The upper end of rod 20 is bent downwardly, as at 31, and its straight downwardly directed part 32 carries a collar 33 on which a spring 34 is resting with its lower end, which is wound about part 31 of rod 20 and the upper end of which is suitably secured to 70 rod 32.

This part 32 of rod 20 is guided within a 75 guide 35 and carries near its lower end a collar 36 against which rests the upper end of a spring 37 wound about rod 32, the lower end of which is secured on said rod. The arrangement of springs 34 and 37 is such that during the downward movement of the part 32 of rod 20 spring 37 will act to cushion the rod while during the upward movement of 80 said part 32 spring 34 will act as cushion.

The extreme lower end of part 32 of rod 20 is angularly bent to form a fork 38 between the prongs of which rod 20 passes and which is secured to the rod as shown.

The operation of my machine will be entirely clear from the above description and by inspection of the drawing, and it will be clear, that upon the vertically reciprocatory movement of the piston rod and piston by means of handle 29, the wash in chamber 24 below piston will be washed, and while the air can escape through openings 23, the water is prevented from entering the space above the piston by the plate valve 25.

It will be understood that I have described 100

and shown the preferred form of my invention as one example of the many possible ways to practically construct the same, and that I may make such changes in its construction as come within the scope of the appended claims without departure from the spirit of my invention.

What I claim as new, and desire to secure by Letters Patent is:

1. In a washing apparatus, a housing, a cylindrical casing on said housing, having an elongated slot, a rod in said casing extending into said housing, a handle on said rod for vertically reciprocating said rod and extending through said slot, a piston at the lower end of said rod, the upper end of said rod bent upon itself, a guide for said bent end, the lower end of said bent end being secured to said rod, means for cushioning said rod during its reciprocation, said piston and its rod reciprocating in said housing, to wash articles in said housing by suction, and a means associated with said piston to allow the escape of air and prevent the passage of water through said piston.
2. In a washing apparatus, a housing, a cylindrical casing on said housing having an elongated slot, a rod in said casing extending into said housing, a handle on said rod for vertically reciprocating the same, and extending through said slot, a piston at the lower end of said rod, the upper end of said rod having a portion bent upon itself, a guide on the casing for said bent end, a fork formed with the lower end of said bent portion, for securing the same to said rod, springs for cushioning said rod during its reciprocation, said piston and its rod reciprocating in said housing to wash articles in said housing by suction, a casing formed with the lower face of said piston, said piston having ports for allowing the escape of air, a housing formed with the lower face of the piston, and a plate valve movable within said housing to prevent the passage of water through the ports in said piston.

In witness whereof I have signed my name to this specification.

WILHELM RATH.
